NEEDLE THREADER

Nils Reinhold Näs, Falun, Sweden

Application July 2, 1946; Serial No. 680,880
In Sweden November 13, 1944

6 Claims. (Cl. 223—99)

1

The present invention has for its object an improved needle-threader.

The main object of the invention is to provide an apparatus for the purpose of facilitating the threading of needles.

It is an object of the invention to provide a simple, inexpensive needle threader which can be operated by the sense of touch alone without the use of the eyes.

It is an object of the invention to provide a needle threader with a needle receiving means having a notch adapted to engage the eye end of a needle in such a manner that the eye of the needle lies in a plane parallel to the moving direction of receiving means whereby the needle may be positioned for threading by the sense of touch alone.

It is an object of the invention to provide a threading hook the motion of which is governed by a cam means such that the initial portion of the path of the hook during the threading operation has a relatively large radius of curvature or is substantially flat and approaches a straight line.

The present invention employs a thread engaging means which while shown as a hook is not limited thereto. The thread engaging means is connected to and guided by a cam means. The term cam means is taken to include all those kinematic arrangements such as cams, and cam followers, linkages, special gearings and the like which will guide the thread engaging means along a preselected path which is preferably a line of variable curvature or even discontinuity lying in or substantially in a single plane. It is the character of this path or plane curve which is one of the specific objects of the invention.

The cam means or guiding structure is so designed kinematically that the needle threading means moves in what may be regarded as distinct steps. While this path of motion may be broken into several parts, the character of two such parts deemed to be of prime importance and will be set forth in certain of the claims. Those two path portions may be termed (a) the thread engaging portion and (b) the needle threading portion. The other parts of the path are not critical.

The thread engaging path portion should be of a quite different character than the needle threading portion. In the thread engaging portion the needle threading means moves over a wide curve or even a straight line until the thread is engaged, then the needle threading means changes the direction of its path or motion

2

abruptly and draws the thread through the needle's eye. Path portion (a) may be the arc of a circle, but its radius is much greater than that of path portion (b). Again, path portion (b) may be thought of as merely a point of very sharp curvature or discontinuity as where two flat curves or lines meet to form an angle. At such a point there is a rapid change of direction which yields the needle threading action.

Whether path portion (b) and the resulting needle threading action flows from a sharp curve in the path of the needle threading means after engaging the thread or flows from an angular change of direction, both are covered by the phrase small radius of curvature. This is true because mathematical points in the present sense are not achieved in physical embodiments of kinematic arrangements and so the path (b) will have physical length and a radius of curvature however small.

Of perhaps equal importance is that feature of the invention which permits its use by the blind. The eye of a needle has two sides separated by a substantial distance. When placed on a flat surface and rotated one can tell by the sense of touch alone if the needle eye is parallel to the flat surface. The needle may be rocked from one side to the other and is in stable equilibrium only when both sides of the needle's eye are resting on the flat surface. This is the same position in which the needle must be to be threaded. It is accordingly an object of the invention to provide a needle receiving notch having a narrow flat bottom only a little wider than the head of a needle. When a needle is placed thereto the walls guide the needle head to the bottom of the notch where it is rotated until a flat side is down and resting on the flat bottom of the notch. The needle threader can then be successfully operated. All of this can readily be done without the use of the eyes. This is a most important function in a needle threader and one which the art has sadly neglected.

A preferred embodiment is shown in the accompanying drawing.

Fig. 1 shows a vertical section of the apparatus. Fig. 2 is a vertical section taken on the line II—II in Fig. 1 of an end portion of the apparatus comprising the threading mechanism. Fig. 3 shows a similar section as Fig. 1 but with the movable members in another working position. Fig. 4 is a top plan view thereof with the eye of a needle. Figures 5 to 8 inclusive show different positions of the threading member during the

course of working. All of the figures are shown in enlarged scale for the sake of clearness.

The threading mechanism is mounted in a double end wall of a box 1, which may serve for keeping a thread reel 3, of which only an end is shown in Fig. 4. The most essential part of the threading mechanism consists of a threading member 4 preferably made of a fine steel wire or the like which is secured in a holder 5, and at its free end is provided with a hook 6, which may pass through the needle eye and catch the thread 7. The holder 5 is substantially square in plan and near one of its edges provided with slots 8, in which the threading member 4 is inserted, so that it is held by the holder 5. At its upper corner at the opposite edge the holder 5 is provided with an ear 9, which is pivoted on a movable slide 10 mounted between the two plates of the end wall 2. Slide 10 is provided with side flanges slidable in grooves 11 in the inner sides of said plates. This slide 10 in its end opposite to the end at which the holder 5 is suspended is provided with a recessed passage 12, through which the threading member 4 is passed. Just above the passage 12 this end of the slide 10 is provided with a notch 13, adapted to engage the needle end provided with the eye 14 in such position of the needle that the opening of the eye lies in a plane parallel to the moving direction of the slide 10. The sliding movement of the slide to the right (according to Figures 1 and 2 in the drawing) is counteracted by a U-shaped spring 16 of which one end is pressed against the right end of the slide 10 and the other end against one side wall of the box. The lower edge of the holder 5 is provided with a cam opening 17, through which extends a pin 18 inserted in the plates 2. Pin 18 operates as a cam follower in the sense that it cooperates with the edges of opening 17 to produce the thread engaging and needle threading movements of hook 6 as described above. In the upper edge of the side wall of the box 1, towards which the end of the slide 10 provided with the notch 13 is directed, a recess 19 is provided, which serves as a seat for the needle 15 in position to be threaded. Recess 19 is just wide enough to receive a needle head without wedging and has a flat bottom on which the needle head may be turned until stable equilibrium is reached. On the upper edge of the right wall plate 2 (according to Fig. 4) a spring holder 20 is secured, under which the thread portion between the needle and the reel is jammed at a desired point, so that the thread may be snapped off at said point, and the thread portion retained by the spring holder 20 is held in correct position for the next threading operation.

In order to thread the needle it is positioned in the recess 19 with the eye end directed against the slide 10 and rotated until one of the flat sides is against the bottom of notch or recess 19 and takes the resting position shown in Fig. 5. After that the slide 10 by means of the needle end is pushed to the position shown in Fig. 3 against the action of the spring 16 acting on the holder 5, by which the threading member 4 is raised. When withdrawing the needle the slide 10 returns by action of the spring, whereby the thread is caught by the threading member 4 and is drawn through the needle eye, as illustrated in Figures 7 and 8. By this operation the bight of the thread 7 threaded through the needle forms a loop, one part of which is jammed between the hook 6 and the walls of passage 12 on

the slide 10, so that a desired length of the thread may be drawn from the reel 3 when the needle 15 is removed from the apparatus. A slight pull is sufficient to release thread 7 from engagement with the hook 6. Thereupon the thread is moved to the spring holder 20, in which the thread is snapped off.

What I claim is:

10. In a needle threader, a body member, slide means mounted on said body member, a track for said slide means, thread holding means mounted adjacent said track and arranged to position a thread at an angle greater than twenty degrees to said track, thread engaging means and cam means comprising a slotted plate and a pin acting on the walls of said slot and controlling the successive positions of said thread engaging means in such a manner as to engage a thread and direct it through the eye of a needle 15 said slot having two substantially parallel walls and a third wall diagonally disposed to said first two walls, all three walls being connected and forming the cam surface of said cam means, said thread engaging means being mounted on said cam means.
20. In a needle threader, thread engaging means, cam control means connected to said thread engaging means, said cam control means comprising a slotted member and a relatively movable member engaging the walls of said slot whereby said thread engaging means is guided into thread engaging position over a smooth path and into needle threading position over a path sharply departing from said smooth path.
30. In a needle threader, thread engaging means, a pivoted member mounting said means, cam means connected to said pivoted member and comprising a cam surface and a cooperating element arranged to ride on a portion of said curved surface, said cam means having a kinematic cycle which imparts an initial rise to said thread engaging means, an intermediate thread engaging relatively flat travel and a needle threading dip to said thread engaging means, said thread engaging relatively flat travel portion of said cycle approximating a straight line.
40. In a needle threader, needle engaging means, thread engaging means movable along a curved path, thread holding means arranged to position a thread across the path of travel of said thread engaging means, a cam member and a cooperating cam follower member, one of said members carrying said thread engaging means, said cam member and said follower member cooperating to produce the curved path of travel of said thread engaging means such that said path has a thread engaging portion of relatively large radius and a needle threading portion of relatively small initial radius of curvature.
50. In combination in a needle threader, a body member, a slide track carried thereby, slide means mounted on said track, a plate pivoted to said slide means, thread engaging means carried by said plate, a cam surface on a portion of said plate removed from said pivot, a cam follower pin carried by said body member and cooperating with the cam surface portion of said plate whereby said thread engaging means undergoes a needle threading cycle comprising a sharp initial rise, an intermediate thread engaging movement of relatively flat travel and a needle threading dip by which a needle is threaded.
60. In a needle threader, thread engaging means mounted for threading movement, pivoted cam means carrying said thread engaging means, said

cam means including angularly disposed relatively straight portions, a follower cooperating with said straight portions whereby upon pivotal movement of said cam means the thread engaging means is initially movable for thread engaging in a path of relatively large radius of curvature and subsequently in a path for needle threading of relatively sharp curvature.
